FIG. 1.

FIG. 2.

FIG. 4.

FIG. 3.

Henry Schlutz

Haville & Haville.

By

Attorney.

UNITED STATES PATENT OFFICE.

HENRY SCHLUTZ, OF PITTSBURGH, PENNSYLVANIA, ASSIGNOR OF TWO-FIFTHS TO
JACOB L. KNOEDLER, OF OPTION, PENNSYLVANIA.

WRENCH.

1,395,656.

Specification of Letters Patent.

Patented Nov. 1, 1921.

Application filed April 20, 1920. Serial No. 375,327.

To all whom it may concern:

Be it known that I, HENRY SCHLUTZ, a citizen of the United States, residing at Mount Oliver, Pittsburgh, in the county of 5 Allegheny and State of Pennsylvania, have invented certain new and useful Improvements in Wrenches, of which the following is a specification.

This invention relates to socket wrenches 10 of the type particularly adapted for use in automobile repair and adjustment work wherein wrenches of the ordinary character are unhandy, due to the peculiar location of the parts of the machine which are necessary 15 of repair or adjustment.

The invention relates particularly to wrenches which may be quickly adjusted to various sizes of nuts or other objects of polygonal form.

20 The invention further contemplates in combination with the wrench, a handle, provided with means at each end for holding the wrench during operations.

An object of my invention is to provide 25 a wrench the jaws of which may be quickly adjusted to grasp polygonal nuts or other objects of polygonal form; and further to provide a wrench extremely simple in operation and of few parts which may be readily 30 assembled and interchanged or substituted when necessary.

Referring to the drawings,

Figure 1 is a side elevation of my wrench and handle, illustrating in full and dotted 35 lines respectively, the manner in which the wrench may be applied to either end of the handle;

Fig. 2 is a longitudinal sectional view of my wrench;

40 Fig. 3 is a transverse section taken on line 3—3 of Fig. 2, and

Figs. 4 and 5 are perspective views at different angles of the jaws of the wrench.

The same reference characters indicate the 45 same parts in all the figures.

Referring now to the wrench 10 represents the body or stock, said stock being elongated and of relatively smaller polygonal cross-section at its lower end 11 50 which is formed with a polygonal socket 12. At its upper end, the stock is formed with a pair of jaw guiding members 14—14¹, connected by an integral yoke 15, which with said jaw guiding members 14—14¹ provide a 55 housing for the shanks 16—17 of the jaws,

to be described, thus effectually securing said jaws against vertical movement as well as lateral movement relative to the said guiding members. 18 and 19 represent the jaws of the wrench carried by said shanks 60 16 and 17, each of said jaws having a socket, the two sockets being of a form suitable to grasp the head of a polygonal nut or bolt or other object which is to be operated. While the jaws and jaw supporting shanks 65 are in general, counterparts, there are certain distinctions between the two which constitute a part of my invention. In the case of each jaw, there is provided an integral spacing portion 20—20¹, respectively, which 70 elevate the jaws in each instance so that its lower edge is flush with or very slightly above the surface of the yoke 15, said spacing portion approximating the thickness of said yoke.

75 Referring first to the jaw 18, it will be observed that the spacing portion 20 is provided with a shoulder 21, which co-operates for interlocking engagement with a correspondingly recessed portion 22 on the end of the shank 17 of the jaw 19 to limit movement of the jaws toward each other. The spacing portion 20¹ of the jaw has a shoulder 23 which co-operates with the end portion 24 of the shank 16 of jaw 18. During adjust- 80 ing operations of the jaws the inner faces of the shanks 16 and 17 bear against each other as will be seen in Figs. 2 and 3, the cross-sectional area of the two when assembled approximating that of the space between the guiding members 14—14¹.

85 Upon the lower outer faces, the shanks 16 and 17 are provided with a series of rack teeth 25 for the purpose to be described. Extending transversely through the stock 90 10 of the wrench, and at right angles to that formed by the guiding members 14—14¹ is an opening 26 adapted to receive rotary operating screws 27 journaled in bearings 28 in the stock of the wrench 100.

The screws which are knurled to facilitate rotation for instance by the thumb, and which extend slightly beyond the opening 26 upon each side of the stock respectively, mesh with the rack teeth upon the jaw 105 shanks 16—17.

110 It will now be seen that rotation of both of the screws in the direction indicated by the arrows in Fig. 2 will cause a simultaneous movement of the shanks alongside of

each other in one direction or the other, depending upon the threading of the screws; that is to say, whether they are right or left hand threads, and the corresponding form 5 of the rack teeth of the shanks of the jaws. The jaws may be readily assembled or disassembled by continuing the movement of the jaws in one direction or the other as the case may be.

10 A novel form of my operating handle is shown in Fig. 1, consisting of an angular bar 29 having on one end, a polygonal socket 30 coöperating with the external lower polygonal end 11 of the stock of the wrench, the 15 other end having a polygonal shank 30, co-operating with the socket 12. It will thus be seen that the connection of the handle at either end with the wrench is readily interchangeable whenever occasion necessitates.

20 I wish it to be understood, that while I have shown and described a particular form of my invention, I do not limit it to the specific structure and details illustrated, as many changes may be made within the scope 25 of the following claims.

Having thus described my invention, what I claim as new and desire to protect by Letters Patent is:—

1. A socket wrench, comprising a stock, 30 having an upper recessed portion, jaws having their complementary shanks slidably mounted within said recess, there being integral spacing portions connecting the

jaws with the shanks, one of said spacing portions being provided with a shoulder, co-operating with a correspondingly recessed portion on the end of the other or complementary shank to limit movement of the jaws toward each other, said jaws having recesses which coöperate to provide a polygonal nut 40 engaging socket, and means for operating said jaws toward and from each other to vary the size of the socket.

2. A socket wrench comprising a stock having a polygonal socket in one end thereof, the other end having a transverse recess and a terminal opening communicating with the recess and disposed at right angles thereto, a yoke spanning the terminal opening, jaws having shanks oppositely slidable lengthwise of the terminal opening beneath said yoke with the lower portions thereof extending transversely of and downwardly into the recess, and each having a series of rack teeth upon the outer faces of the lower 55 portions thereof, operating screws journaled transversely of said recess below the terminal opening and upon opposite sides of the lower portions of the shank and meshing with the rack teeth on said jaw shanks, said screws 60 projecting slightly beyond the walls of said recess to facilitate engagement by the hand for rotation whereby said jaws are moved toward or away from each other.

In testimony whereof I affix my signature. 65
HENRY SCHLUTZ.
